UNITED STATES PATENT OFFICE.

STEPHEN H. COOMBS, OF CHICAGO, ILLINOIS.

BEATER.

No. 865,999.

Specification of Letters Patent.

Patented Sept. 17, 1907.

Application filed November 10, 1906. Serial No. 342,832.

To all whom it may concern:

Be it known that I, STEPHEN H. COOMBS, a resident of Chicago, in the county of Cook and State of Illinois, have invented certain new and useful Improvements 5 in Beaters, of which the following is a full, clear, and exact description.

The present invention relates to devices for beating or whipping cake-batter, cream, eggs, etc.

The invention designs to provide a device for the 10 purposes stated which is simple in construction, and efficient in operation. It is well known in the art that the most effective and quickest method of beating batter etc., to make it light, is by using two ladles or paddles one in each hand, and beating the material by 15 continuous circular motion of each ladle in paths intersecting each other, and the invention also designs to provide an improved device in which the beating operation is substantially the same as the familiar paddles to affect the material in the same manner as when 20 it is done by hand but with greater speed.

In the operation of the beaters embodying the inventions set forth in Letters Patent of the United States No. 573,208 and No. 673,198, granted to me, in which the beaters are respectively connected to cranks 25 revolving in opposite directions, the beater-blades are moved laterally in the same direction and vertically in opposite directions, it being impossible when oppositely rotating cranks, which are directly connected to the beater-levers are employed to attain both vertical 30 and lateral movement of the beater-blades in opposite directions.

The present invention also designs to provide an improved construction in which a simple operating mechanism can be used and a plurality of beaters may be 35 driven by cranks oppositely disposed and rotating in the same direction to cause the blades to move laterally and vertically in opposite directions relatively.

The invention consists in the several novel features hereinafter set forth and more particularly defined by 40 claim at the conclusion hereof.

In the drawings: Figure 1 is a view in side elevation of a device embodying the invention, the batter-pan being shown in section. Fig. 1^a is a detail view of the supporting-frame. Fig. 2 is a section on line 2—2 of 45 Fig. 1. Fig. 3 is a section on line 3—3 of Fig. 1. Fig. 4 is a section on line 4—4 of Fig. 1. Fig. 5 is an end elevation of the device, the batter-pan being shown in section. Fig. 6 is a horizontal section taken on line 6—6 of Fig. 5. Fig. 7 is a side-elevation of a device 50 embodying a modified form of the invention. Fig. 8 is a vertical section thereof, and Fig. 9 is a plan of the adjustable pan-support.

In the form of the invention illustrated in Figs. 1 to 6, the device is adapted to rest on the top of a batter-pan 12, of usual form, and to be held in operative posi-

tion thereon by the operator, this form being one more generally used for the smaller sizes of beaters and in households. A supporting-frame adapted to rest on the pan and in which the operating parts of the device are mounted, comprises a pair of arched bars 13 having 60 legs and feet 14 adapted to fit around the upper edge of the batter-pan to centralize and position the device with respect to the pan or bowl. These arched bars are preferably formed of a strip of metal bent to form the legs and feet. A pair of frame-bars are riveted to 65 the arch-bars as at 16 and are extended inwardly therefrom to form uprights 17 which are secured together and between these uprights the bearings and guides for the operating parts are mounted. The bars from which the frame-members 17 are formed are also ex- 70 tended upwardly from the points at which they are secured to the arch-bars to form braces 18 extending upward diagonally and secured to the uprights as at 19 to render the supporting-frame laterally rigid. This construction and arrangement of the supporting-frame provides a simple way of forming a rigid frame from the bars or strips of metal which can be readily formed by dies. To the upper ends of the uprights of the supporting-frame is secured a handle 20 whereby the device and frame can be held downwardly upon the 80 batter-pan and to hold the device in operative relation with respect thereto.

A bushing or journal sleeve 21 is secured between outwardly bent portions 17^a of uprights 17 to provide a journal for a main drive-shaft 22. At one side of the 85 frame the drive-shaft has secured thereto a gear 23 and to its other end a crank or handle 24 whereby the operator can impart movement to the drive-shaft. Below the drive-shaft a bushing or bearing-sleeve 25 is secured between outwardly bent portions of the up- 90 rights in which a crank-shaft 26 is journaled. A pinion 27 secured to shaft 26 meshes with and is driven by, gear-wheel 23. To the opposite ends of shaft 26 are respectively secured oppositely disposed cranks 28 and 29 whereby the beater-levers are respectively oper- 95 ated, each crank being provided with a wrist-pin 35. Beater-blades 30 each comprise a pair of inwardly ex- 100 tending arms 31 and a connection-portion arranged at the outer side. Each beater-blade is secured to a beater-lever 15 or support preferably (but not essen- 105 tially) formed of a rod or strip which is bent to form a pair of upright members 32 which extend upwardly from the beater and are bent towards each other as at 33 and between said bent portions is secured a cross head or block 34 to which an eccentric-pin 35 is con- 110 nected. A rivet 37 extending through block 34 and the uprights, rigidly secures the block to the uprights. The members of the beater-levers are also spread as at 38 to clear the main drive-shaft and operating-handle during the operation of the device. A stud or tube 39 is se-

cured between the uprights of the supporting-frame and the upper portions of the members of the beater-levers are bent to form ways for stud 39 and by which the upper ends of the levers are slidably connected to 5 the frame so they can move vertically. By providing guides at one end, for one end of each lever, and eccentric connections between the guides and the blades there is less angular movement of the levers which renders them easy to operate.

- 10 In operation, movement, manually imparted to the operating-crank or handle 24 will drive gear 23 which in turn will rapidly rotate pinion 27 to impart continuous rotation in one direction to the cranks 28 and 29 and wrist-pins 35. The oppositely disposed eccentric 15 connections between the beater-levers and the operating-means rotating in the same direction will operate the levers and beaters to travel in opposite directions both laterally and vertically and continuously stir the batter, *i. e.*, the batter will be beaten to move in a substantially elliptical path the same as is done when using 20 two paddles to stir the batter. This has been found in practice to be a most efficient movement and to result in making the batter light.

In Figs. 7 to 9, there is shown a modified form of the 25 invention which is designed more particularly for the larger sizes of beaters and in which a different supporting-frame is provided. In this form of the invention the frame comprises an arch 40 and a standard 41 secured thereto at its upper end and also by a curved strip 42. The main operating-shaft 43 is journaled in uprights 41 and a standard 41' secured at its upper end to arch-bar 40 and at its lower end to a cross-bar 41^a. One end of drive-shaft 43 has secured thereto a gear-wheel 44 arranged to engage a pinion 45 which is connected to 30 drive a fly-wheel 46. In this construction the eccentric-shaft 26 and guides 39 are mounted in standard 41^a. The operating-mechanism for the beaters is the same as that hereinbefore described. An adjustable pan-support 35 comprises two members which are formed of a bar bent as at 48 to fit around the pan and secured together by blocks 49. The ends of the pan-supporting bars extend outwardly alongside of the bars 40 to guide the support vertically. To adjustably sustain the pan-support at the desired elevation, the bars 40 have formed therein notches or teeth 50 which are adapted to be engaged by and hold dogs 51 which are pivotally sustained in the pan-support as at 52. The dogs are provided with extensions 53 which may serve as weights to hold them in operative position. When the dogs are 45 released, the pan-support is free to be lowered. Stops 54 may be provided for the pan-support.

The invention provides a simple construction for a device of the character described which has been found to be most efficient in practice. It possesses several 50 important advantages. It provides an advantageous movement for the beaters. By providing guides at the upper ends of the levers less power is required to operate the levers and beaters than heretofore. The supporting-frame, being made by dies, can be produced at 55 a low cost.

The invention is not to be understood as restricted to the details set forth and described but may be modified by the skilled mechanic without departing from the spirit and scope of the invention.

Having thus described the invention, what I claim 65 as new and desire to secure by Letters Patent, is:

1. In a device of the character described, the combination of a supporting-frame, an eccentric-shaft journaled in the frame, a pair of beater-levers each provided with a blade at its lower end, mechanism for driving said shaft, 70 oppositely disposed eccentric connections between said shaft and said levers respectively, and slidable connections for guiding the upper ends of the levers vertically.

2. In a device of the character described, the combination of a supporting-frame, an eccentric-shaft journaled in said frame, driving-mechanism, a pair of beater-levers each provided with a blade at its lower end, oppositely disposed eccentric-pins secured to said shaft so as to rotate in the same direction and respectively connected to said levers, and slidable connections for guiding the 80 upper ends of the levers vertically.

3. In a device of the character described, the combination of a supporting-frame, a pair of levers each provided with a beater-blade at one end thereof, slidable connections for the other end of said levers for guiding them 85 longitudinally, operating-means connected to said levers medially and between the guides and the blade, for operating the beaters longitudinally and laterally in opposite directions.

4. In a device of the character described, the combination of a supporting-frame, a main-drive-shaft mounted therein, an eccentric-shaft mounted therein and provided with wrist-pins oppositely arranged with respect to one another, a single gear-connection between said crank-shaft and the main drive-shaft, a pair of beater-levers 95 each provided with a beater-blade and connected to the wrist-pins respectively, and means for slidably connecting the upper ends of the lever to the frame.

5. In a device of the character described, the combination of a supporting-frame, an eccentric-shaft mounted 100 therein, drive-mechanism mounted in the frame, a pair of beater-levers each provided with a blade at its lower end, oppositely disposed eccentric connections between the crank-shaft and the levers respectively, and stud-and-slot connections between the supporting-frame and the upper 105 ends of said levers.

6. In a device of the character described, the combination of a supporting-frame, a pair of levers each provided with a beater-blade at its lower end, drive-mechanism, eccentric connections between the drive-mechanism and 110 said levers comprising wrist-pins, said levers being formed of rods extending upwardly from the beater-blades, wrist-pin blocks rigidly secured between the rods said rods being extended upwardly above the wrist-pin connections to form a slidable connection for the upper end of the lever, 115 and means on the frame extending into said guide.

7. In a device of the character described, the combination of a supporting-frame comprising uprights formed of bars or strips of metal, a bushing or sleeve secured between said uprights, a shaft journaled in said sleeve, a 120 pair of beater-levers each provided with a beater, drive-mechanism for said shaft, and operating-connections between said levers and said shaft.

8. In a device of the character described, the combination of a supporting-frame formed of strips or bars of metal and comprising uprights, a pair of beater-levers each provided with a blade at its lower end, a bushing or sleeve secured between said uprights, a shaft mounted in said sleeve and provided with lever-operating means, and 125 drive-mechanism for said shaft.

9. In a device of the character described, the combination of a supporting frame formed of strips or bars of metal and comprising a pair of uprights, a sleeve or bushing secured between the uprights, a shaft journaled in said sleeve, an eccentric-shaft also mounted in said frame and 130 a pair of beater-levers operatively connected to the driving mechanism and provided with a blade at its lower end.

10. In a device of the character described, the combination of a supporting-frame formed of bars or strips bushing or bearing sleeves secured between the uprights of said frame, a drive-shaft mounted in one of said bushings, an eccentric-shaft mounted in the other bushing, a driving 140

connection between said shafts, a pair of beater levers each provided with a beater-blade at its lower end, and operating-connections between the eccentric-shaft and said levers.

- 5 11. In a device of the character described, the combination of a supporting-frame formed of strips or bars of metal comprising a pair of upright-bars between which a pair of bushings or sleeves are secured, a drive-shaft journaled in one of said bushings, an eccentric-shaft journaled in the other of said bushings, a pair of beater-levers each provided with a blade at its lower end, operative connections between the levers and the driving mechanism, and a lever-guide secured between said uprights.
12. In a device of the character described, the combination of a supporting-frame, a crank shaft journaled in said frame, a drive-shaft also journaled in said frame and above the crank-shaft, a driving-connection between said

shafts, a pair of beater levers each provided with a blade at its lower end and connected medially to the crank-shaft one of said levers being extended around the drive-shaft, 20 and means for vertically guiding the upper ends of said levers.

13. In a device of the character described, the combination of a frame provided with feet adapted to rest on the upper edge of a pan or bowl and to be held in position 25 with respect to the pan or bowl by said feet, drive-mechanism mounted in said frame, a pair of beater levers each provided with a blade, and operating-connections between the blades and the drive-mechanism for operating them vertically and longitudinally.
